CLAIM

The ornamental design for a blood filter and tubing harness for extracorporeal blood treatment, as shown and described.

DESCRIPTION

FIG. 1 is a front, top, right side perspective view of the blood filter and tubing harness for extracorporeal blood treatment; FIG. 2 is a left elevational view of the harness shown in FIG. 1;

FIG. 3 is a right elevational view of the harness shown in FIG. 1;

FIG. 4 is a front elevational view of the harness shown in FIG. 1;

FIG. 5 is a rear elevational view of the harness shown in FIG. 1;

FIG. 6 is a top plan view of the harness shown in FIG. 1;

FIG. 7 is a bottom plan view of the harness shown in FIG. 1; and,

FIG. 8 is a perspective view of the harness shown in FIG. 1 wherein dotted lines are used to show a blood filter and tubing which are not part of the claimed invention.
